UNITED STATES PATENT OFFICE.

CHARLES E. PERRING, OF NEW YORK, N. Y., ASSIGNOR TO THE GLEASON-TIEBOUT
GLASS COMPANY, A CORPORATION OF NEW YORK.

DESIGN FOR AN ARTIFICIAL-LIGHT SHADE.

40,706.

Specification for Design.

Patented May 24, 1910.

Application filed March 5, 1910. Serial No. 547,615. Term of patent 7 years.

To all whom it may concern:

Be it known that I, CHARLES E. PERRING, a citizen of the United States, and resident of the city, county, and State of New York, have invented a certain new, original, and ornamental Design for Artificial-Light Shades, of which the following is a specification, reference being had to the accompanying drawing, forming part thereof, in which—

Figure 1 is a side elevation and Fig. 2 an inverted plan or bottom view of my new design.

I claim:

The ornamental design for an artificial light shade, as shown.

CHARLES E. PERRING.
